(57) **CLAIM**

The ornamental design for a charging station for electric vehicles, as shown and described.

DESCRIPTION

The patent or application file contains at least one drawing executed in color. Copies of this patent or patent application publication with color drawing(s) will be provided by the Office upon request and payment of the necessary fee.

1. Charging station for electric vehicles

1.1 is a front elevation view of a charging station for electric vehicles;

1.2 is a front, left side perspective view thereof;

1.3 is a front, right side perspective view thereof;

1.4 is a left side elevation view thereof;

1.5 is a right side elevation view thereof; and,

1.6 is a rear elevation view thereof.
